CLAMP

Francis Turzicky, Chicago, Ill., assignor to Illinois
Malleable Iron Co., Chicago, Ill., a corporation
of Illinois

Application April 5, 1940, Serial No. 327,945

14 Claims. (Cl. 24—126)

This invention relates to clamps, and with regard to certain more specific features to guy clamps.

Among the several objects of the invention may be noted the provision of a safe, compact and easily operable guy clamp in which a plurality of gripping portions is provided to effect maximum grip with minimum clamping force applied to a single member; the provision of a guy clamp of the class described which substantially makes coaxial the members which it joins; and the provision of a guy clamp of the class described which may be readily carried out in forms which are adaptable to various requirements of attachment. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which are illustrated three of various possible embodiments of the invention—

Fig. 1 is a fragmentary side elevation showing the application to a guy wire of various forms of the invention;

Fig. 2 is a longitudinal section of one form of the invention;

Fig. 3 is a cross section taken on line 3—3 of Fig. 2;

Fig. 4 is a cross section taken on line 4—4 of Fig. 2;

Fig. 5 is a view similar to Fig. 2, showing another form of the invention;

Fig. 6 is a right-side elevation of the inner plug only, of Fig. 5;

Fig. 7 is a bottom plan view of Fig. 6;

Fig. 8 is a view similar to Fig. 2, showing another form of the invention inverted;

Fig. 9 is a right-side elevation of the inner plug part of Fig. 8;

Fig. 10 is an end view of the outer casing of all forms of the invention;

Fig. 11 is a side elevation of a modified form of the invention including a ground wire clamp; and,

Fig. 12 is a cross section taken substantially on line 12—12 of Fig. 11.

Fig. 10 represents a plan view of the outer casing per se if viewed from the top of Fig. 8 or bottom of Figs. 2 and 5, but as applied to Figs. 2 and 5 and viewed from the bottom, this casing is turned through 180°.

Similar reference characters indicate corresponding parts throughout the several views of the drawings.

Referring particularly to Fig. 1, there is shown at numeral 1 a pole braced by an anchor rod 3.

At numeral 5 is shown a bracket held in place to the pole by means of a bolt 7. Between the anchor rod and the pole bracket is a guy wire assembly with the various forms of the invention applied thereto, by way of example.

The three forms of the invention hereinafter to be described will be designated as forms A, B and C. All of these forms are indicated on Fig. 1.

Form A is detailed in Figs. 2, 3, 4 and the generally applicable Fig. 10. Referring particularly to Fig. 2, there is shown at numeral 9 a generally cylindric outer casing or body which is externally circular, except for a flat wrench-engaging portion 11. The slight taper shown is for convenience in manufacture. This casing, as indicated in Fig. 10, has an interior which is generally cylindric as indicated at 12, but which has extending into the cylinder 12 a large (or high) wedge-shaped portion or spline 13. Upon the inner edge of wedge 13 is a groove 15 forming a cradle for reception of the one leg of a looped portion 17 of a guy 19. The end 21 of the wedge 13 is so positioned that the center line of the applied guy 19 is positioned approximately upon the center line of the cylindric portion 12.

On the other side of the casing 9 is a similar but smaller wedge-shaped portion 23 which likewise has a groove 25 for the reception of another leg part of the loop 17. This wedge-shaped portion does not extend radially inward so far toward the center line of the casing 9 as does the wedge 13. Adjacent to the end of the wedge 23 there is formed, through the casing 9, a notch 27 of a size which permits the end 29 of the loop 17 to bend sidewise and out of the casing 9 (Fig. 2).

Slidably cooperating internally with the cylinder 9 is an inner, approximately cylindric plug 31. This plug is threaded at one end as indicated at 33 for the reception of a threaded nut 40 which works against the lower end of the outer casing 9 to draw the plug into the casing.

The plug 31 includes a deep groove 35 which is shaped to fit and accommodate the deep wedge 13 when the plug 31 is moved axially into the casing 9. This groove 35 slopes to provide the hollow counterpart of the solid wedge 13, and ends in an axial relationship with respect to the guy 19 as indicated in Fig. 2.

Opposite the groove 35 in the plug 31 is a second more shallow groove 37 which receives the wedge 23.

Both grooves 35 and 37 at their upper ends in Fig. 2 are only about half as deep as required by the diameter of the loop 17, as indicated at 39, the other halves of the required passages at these points being indicated at grooves 41 in the casing. Thus, grooves 41 form continuations of grooves 35 and 37. Thus, the sides of the loop 17 are directed outward to 60

- obtain a large opening in the guy eye loop. The center "O" of the eye is coaxial with the axis of the main guy 19, as determined by the wedge 21 and the grooves 35 and 37.
- 5 To operate the device, the nut 34 is removed and the plug 31 separated from the casing 9. The guy 19 is threaded through the nut 34 and casing 9 and one side of the loop 17 is laid upon the wedge 13. The other side of the loop 10 is laid against the wedge 23. The plug 31 is then inserted within the loop and moved axially into position within the casing 9 with the groove 35 adjacent the wedge 13 and the groove 37 adjacent the wedge 23. This places some of the 15 threads 33 clear of the lower end of the casing 9 and permits application of a wrench and drawing up of the nut 34. The nut 34 reacts against the lower end of the casing 9 to draw the plug 31 into the casing 9. The portions 13 and 23 20 in grooves 35 and 37 respectively function not only as wedges but also as spline connections which permit relative longitudinal movement and prevent relative rotary movement as the nut 34 tends to rotate the case 9 on the plug 31. 25 Thus they avoid the necessity for the wire 19 resisting a shearing twist during tightening.
- The stub end 29 of the loop 17 is led out through the notch 27 and bound against fraying, if desired, as indicated at 43. It will be 30 understood that if desired the end 29 of the guy may be brought out through the lower end of the groove 37 and below nut 35.
- Application of the A form of the device of Figs. 2, 3 and 4 is shown in two places in Fig. 1 35 wherein the loops 17 loop around suitable eyes in an insulator 45. The loops are connected by the respective clamps of the A form to guy wires 19 as indicated.
- In Figs. 5, 6, 7 and 10 is detailed the alternative 40 B form of the invention, in which like numerals designate like parts so far as applicable. The difference in this case is that the plug 31 is provided with an integral extension 47 which forms a fixed eye for predeterminedly forming and 45 supporting the loop 17. This permits the loop to be applied to a bracket such as 5 without wearing the guy wire. In this case, the grooves 35 and 37 in the plug 31 are simply extended around the eye 47 as indicated at 49 in Figs. 6 and 7.
- 50 Fig. 7 shows to good advantage the appearance from the bottom of the grooves 35 and 37, as applied to all forms of the invention. The practical application of the B form of the invention is shown at the upper end of Fig. 1, wherein the 55 rigid eye 47 is supported by the bracket 5.
- In Figs. 8, 9 and 10 are shown details of the C 60 form of the invention in which also like numerals designate like parts. In this case the casing 9 and plug 31 are usually inverted as a whole (not relatively). In this form of the invention, the plug 31 is extended (down, if inverted as shown) by means of a solid and more or less cylindric head 51 which has a threaded socket 53 for receiving a threaded anchor rod 3.
- 65 The grooves 35 and 37 are then continued upwardly as a groove 51 which extends around the side of the cylindric extension 51, that is, around and not touching the threaded end of the anchor rod 3.
- 70 The guy 19 is preferably of the metallic type, that is, a guy wire or cable made up of one or more twisted wires or the like. However, the invention is applicable in all sizes to guys made of other material, such as rope, solid bendable 75 wires, and the like.

The cylindric form of the casing 9 and of the plug 31 is not limiting, since other shapes may be used, such as cones, hexagons and like tubular forms. The form is preferred, however, which permits free cooperation at any endwise 5 position of the wedges 13 and 23 with the respective grooves 35 and 37 so as not to interfere with clamping the wire.

The device is very compact and presents no catching portions requiring protection. It is 10 self-centering and easily drawn up by a single rotary operation on the nut 34.

The diametrically opposed positions of the wedges in the body 9 and the grooves in the plug 31 cause the action and reaction between these 15 to support the plug on the legs of the loop of the guy, without the plug being unnecessarily forced into direct lateral contact with the body 9. Thus, in connection with any amount of clearance between the plug and the groove, the 20 plug may move endwise easily without substantial friction between the plug and the body.

In Figs. 11 and 12 is shown a modification in which like numerals designate like parts. In this form of the invention, flats 61 are employed on the sides of the body 9 for the flat sides of a U-bolt 63, which encircles the body. A cross member 65 is held by nut 67 on the U-bolt and has a notch 69 opposite a notch 71 on the body 9 for receiving and clamping a 30 ground wire 73.

The various applications shown in Fig. 1 are exemplary and others may be used.

In view of the above, it will be seen that the several objects of the invention are achieved and 35 other advantageous results attained.

As many changes could be made in the above constructions without departing from the scope of the invention, it is intended that all matter contained in the above description or shown in 40 the accompanying drawings shall be interpreted as illustrative and not in a limiting sense.

I claim:

1. In apparatus of the class described, a guy having looped legs, a tubular body, inwardly 45 extending axial wedges from said body upon which said legs are carried, a plug axially movable within the body and loop and containing axial tapered grooves cooperating with said axial wedges to hold said legs, said plug being threaded 50 at one end, and a nut engaging the threads on the plug and reacting on the body to draw the plug so as to clamp the legs between the grooves and wedges.

2. A guy clamp for a guy having a loop, said 55 clamp comprising a tubular body, diametrically opposed axial wedges extending inwardly from said body, a plug freely and axially movable within the body and having diametrically opposed axial and tapered grooves cooperable respectively 60 with said wedges, said plug being threaded at the end adjacent the deepest portion of said tapered grooves, said loop being at the opposite end, and a nut engaging the threads of the plug.

3. In apparatus of the class described for a 65 guy having looped legs, a substantially cylindric and tubular body, diametrically placed wedges extending inwardly from said body upon which said legs are cradled, one of which wedges extends substantially to the center line of the body 70 to place one leg axially where it enters the body, and the wedge extending in not so far, a substantially cylindric plug having diametrically opposed and tapered grooves for engaging said legs upon the wedges, one of said grooves being deeper 75

than the other for engagement with the leg on the deep wedge and having an outlet near the center line, said plug being threaded at the end adjacent the deepest portions of the wedges, and 5 a nut engaging the threads of the plug and reacting against the body to draw the plug against said legs.

4. In apparatus of the class described, a guy having looped legs, a tubular body around said 10 looped legs, inward extending wedges from said body upon which said legs are supported, a plug axially movable within the body and loop and containing tapered grooves to cooperate with said wedges to hold said legs and to provide a splined 15 connection with the tubular body, means reacting against the body to draw the plug therein, and a wrench-engaging portion on the body.

5. In apparatus of the class described, a guy having looped legs, a tubular body around said 20 looped legs, inward extending wedges from said body upon which said legs are supported, a plug axially movable within the body and loop and containing recesses to cooperate with said wedges to hold said legs and to provide a splined 25 connection with the tubular body, means reacting against the body to draw the plug therein, and an eye extending from the opposite end of the plug.

6. In apparatus of the class described, a guy 30 having looped legs, a tubular body around said looped legs, inward extending wedges from said body upon which said legs are supported, a plug axially movable within the body and loop and containing recesses to cooperate with said wedges 35 to hold said legs, means reacting against the body to draw the plug therein, and an eye extending from the opposite end of the plug and having grooved means supporting the loop to predetermine its shape and to support it.

7. In apparatus of the class described, a guy 40 having looped legs, a tubular body around said looped legs, inward extending wedges from said body upon which said legs are supported, a plug axially movable within the body and loop and containing recesses to cooperate with said plug 45 to hold said legs, means reacting against the body to draw the plug therein, and means extending from the opposite end of the loop adapted for attachment of an anchor rod or the like and being laterally grooved to support the loop adjacent to the end of said rod.

8. A guy clamp comprising an outer hollow case, an inner plug axially movable therein, inner grooved extensions in the case, one of which accommodates the leg of a guy loop on the axial center of the case, said plug having cooperating 55 grooves to effect clamping engagement upon the guy loop in cooperation with said wedges and providing a splined connection between the case 60 and plug, said plug having a length so that when cooperatively engaging the loop it extends from the case, threads on the plug where it extends from the case, a nut on the threads and engageable with the end of the case to forcefully draw 65 the plug into the case to clamp the guy against both of said wedges, and a notch at the end of the case adjacent to but within the nut to permit exit therefrom of the end of the other leg of the guy loop.

9. A guy clamp comprising an outer hollow case, an inner plug axially movable therein, inner grooved web extensions in the case, said plug having cooperating grooves to effect clamping

engagement upon the legs of a guy loop in cooperation with said wedges, said plug having a length so that when cooperatively engaging the loop it extends from the case, threads on the plug where it extends from the case, a nut on the threads and engageable with the end of the case to forcefully draw the plug into the case to clamp the guy against both of said wedges, and rigid means extending from the unthreaded end 5 of the plug adapted physically to support the loop 10 of the guy which extends from the case, said last-named means comprising an eye having an exterior groove forming an extension from said grooves in the plug.

10. A guy clamp comprising an outer hollow 15 case, an inner plug axially movable therein, inner grooved extensions in the case, said plug having cooperating grooves to effect clamping engagement 20 upon the legs of a guy loop in cooperation with said wedges, said plug having a length so that when cooperatively engaging the loop it extends from the case, threads on the plug where it extends from the case, a nut on the threads and engageable with the end of the case to forcefully 25 draw the plug through the case to clamp the guy 30 against both of said wedges, and means extending from the unthreaded end of the plug grooved laterally to laterally support the loop of the guy which extends from the case, said last-named means comprising an axially solid extension having a threaded recess for reception of a threaded rod to place the latter coaxial with respect to the guy.

11. A guy clamp comprising an elongated body 35 portion having on one side a notch for receiving a ground wire, a U-bolt surrounding said body portion, a clamping member associated with the U-bolt and adapted to be forced against said ground wire adjacent to said notch.

12. A guy clamp comprising an elongated body 40 portion having on one side a notch for receiving a ground wire, a U-bolt surrounding said body portion, a clamping member associated with the U-bolt and adapted to be forced against said ground wire adjacent to said notch, and at least 45 one flat portion on the body and a corresponding flat portion on the U-bolt, said flat portions being adapted to engage one another to guide the U-bolt.

13. A guy clamp comprising a tubular member, 50 a plug member within the tubular member and shaped for axial movement therein, at least two tapered splines on one of said members and each extending into a tapered groove in the other of said members, said grooves accommodating the 55 splines for axial movement without relative rotation, said tapered splines and grooves having cooperating clamping surfaces for a looped strand which is thereby adapted to be held.

14. A guy clamp comprising a tubular member, 60 a plug member within the tubular member and shaped for axial movement therein, wedge-shaped splines extending inwardly from the tubular member, said plug member having axial grooves receiving said splines for longitudinal movement 65 without relative rotation, the grooves having wedge-shaped bottoms cooperating with the wedge-shaped splines to clamp a looped strand, said tubular member having an outlet adjacent to its spline for the end of the strand, and a 70 nut threaded to the plug and being rotary against the axially movable tubular member.

FRANCIS TURZICKY.
